UNITED STATES PATENT OFFICE.

BENJAMIN R. DAVISSON, OF DUARTE, CALIFORNIA.

PIPE-MOLD.

SPECIFICATION forming part of Letters Patent No. 683,389, dated September 24, 1901.

Application filed April 4, 1900. Serial No. 11,515. (No model.)

To all whom it may concern:

Be it known that I, BENJAMIN R. DAVISSON, a citizen of the United States, residing at Duar-
5 arte, in the county of Los Angeles, State of California, have invented new and useful Im-
provements in Pipe-Molds, of which the follow-
ing is a specification.

My invention relates to molds for forming concrete pipe; and the objects thereof are to
10 provide a mold of simple construction that will permit the formation therein of pipe of great density and strength and which can be readily removed from the pipe when completed without collapsing the core, and there-
15 by insure a smooth interior in the pipe. In the manufacture of concrete pipe with the cores heretofore employed difficulty has been encountered in thoroughly compressing the concrete by tamping or pressing, as the cores
20 are collapsible or yielding in order that they may be removed from the concrete when formed, and therefore do not form a suitable inner mold for the concrete when being formed into pipe. This will be obviated by my im-
25 proved core. I accomplish these objects by the mechanism described herein and illus-
trated in the accompanying drawing, forming a part hereof, which is a vertical section of my pipe-mold, showing concrete therein.
30 A is the outside casing of the mold, which is held together in the usual manner and is provided with handles B. Casing A rests upon bottom block C, which is provided with a round hole D in the center thereof, adapted
35 to fit upon the smaller end of the core E, which projects a short distance below block C when the mold is in place ready for use to enable the removal of the core when the pipe is removed to the drying-floor. Block C is
40 supported by timber F, which rests upon the ground or floor G when the pipe is being made. Core E is made with a slight taper from the top to the bottom to permit of its easy withdrawal from the concrete forming
45 the pipe. I have found in practice one-fourth of an inch taper to be amply sufficient in a joint thirty inches long. Core E is made of a continuous shell and is braced internally by ribs H H, through which pass rod I, hav-

ing on the upper end thereof handle J, with 50 which to handle core E and to facilitate its removal from the concrete when completed. Resting on block C and extending from cas-
ing A to core E is chime-ring K to form a proper chime on the lower end of the joint of 55 pipe to receive the upper end of the joint of pipe, which is formed into proper shape by shaper-ring L.

My mold is operated as follows, the parts being assembled as shown in the drawing, ex- 60 cept shaper-ring L: Concrete M of proper consistency to make pipe is fed between the casing and the core and is thoroughly tamped. As core E is a continuous shell, it permits of the concrete being more thoroughly tamped 65 than if made in the usual collapsible form. When the mold is full, an additional quan-
tity of concrete is placed on the top and shaper-ring L is then put on and the top is formed into proper shape thereby to fit the 70 lower end of another joint, and the joint and mold are then removed to a suitable drying-
floor. Upon setting the mold down upon the drying-floor core E comes in contact therewith and by a gentle pressure of handles B is started 75 out of the pipe and is removed therefrom by handle J, after which the outer casing is re-
moved in the usual manner and, together with the core, may be used again. As the core is
80 continuous, the inner side of the pipe is ren-
dered much smoother than with the collapsible core. Pipe made from my mold should be laid from the outlet to the inlet of the line.

Having described my invention, what I claim is—

In a mold for making cement pipe, the com-
bination with a non-collapsible taper core,
having its smaller end adapted to project be-
low the end of the mold, of a base-block and
an outer casing.

In witness that I claim the foregoing I have hereunto subscribed my name, this 28th day of March, 1900, at Los Angeles, California.

B. R. DAVISSON.
